UNITED STATES PATENT OFFICE.

JACOB KERSTEN, OF KALAMAZOO, MICHIGAN.

RADIO LOUD-SPEAKER.

Application filed March 28, 1927. Serial No. 178,850.

This invention relates to a sound amplifying and modulating construction designed to be used in connection with a radio loud speaker unit. It is an object and purpose of the present invention to make a device of this character in a simple and economical manner, which will be attractive in appearance and with which blasting of sound at certain pitches thereof is obviated. A further object of the invention is to provide a construction of this character wherein an amplifying horn is not only housed within an outer enclosing housing but it, with the housing, is mounted upon and carried by a supporting base, all of the parts being secured together by a very simple and practical construction. The invention consists in many novel constructions and arrangements of parts going to make up the complete device which will be fully understood from the following description taken in connection with the accompanying drawings, in which,

Fig. 1 is a front elevation of the sound amplifier.

Fig. 2 is an enlarged vertical section through the construction shown in Fig. 1.

Fig. 3 is a fragmentary enlarged vertical section through the lower part of the construction illustrating the manner in which the horn and its housing are connected with the supporting base.

Fig. 4 is a horizontal section through the construction shown in Fig. 1, the plane of said section being slightly above the center of the housing, and

Fig. 5 is an elevation of the amplifying horn which is housed within said housing.

Like reference characters refer to like parts in the different figures of the drawings.

The horn which is used is made of suitable material including paper, plaster of Paris composition, burlap and knitted fabric, the details of the process of construction of which form no part of the present invention. It includes a vertical neck 1 at its lower end, from which the horn extends to one side and upwardly with the progressive enlargement as indicated at 2, being thence turned back and considerably enlarged and terminating the spaced apart sides 3 and 4 connected by an integral curved portion 5, the lower edges 6 of the sides 3 and 4 being located in a substantially horizontal plane. The open end of the amplifying horn is of large size and the edges 6 of said sides 3 and 4 lie in substantially a horizontal plane.

At the lower end of the neck 1 a metal sleeve 7 is located being both interiorly and exteriorly threaded at its lower end. Into the upper end of the metal sleeve 7 a longer sleeve 8 of thin sheet metal is inserted and firmly secured as by soldering, the upper portion thereof extending into the lower end of the neck 1 of the horn. In practice the neck 1 of the horn is built around the sleeve 8 so that the outer sides of the walls of the neck come substantially in alignment with the outer sides of the sleeve 7 as best shown in Fig. 3.

The housing in which the horn is located is made of two parts 9 and 10 each of which is of conical form. The side 9 is the rear of the housing and the side 10 the front side. The front side 10 has a number of openings cut therethrough in accordance with any predetermined artistic design and on the inner side of the side 10 a screen 11 is secured, passing over the openings so as to make a better appearance. The screen is of open mesh, that the sound waves may readily escape.

The edges of the two sides 9 and 10 of the housing are brought together and the rear side 9 lies snugly against the rear side 4 of the horn. In the same manner, those parts of the front side 10, left after the openings are cut therethrough press against the front side 3 of the horn. A rod 12 threaded at both ends passes through the centers of and lies between the conical sides 9 and 10 and at each end is equipped with a nut 13 of the form best shown in Fig. 2. The rod 12 lies immediately underneath the lower edges 6 of the sides 3 and 4 of the horn and serves to hold the enlarged portion or bell of the horn in the upper part of the housing; and when the nuts 13 are tightened snugly to place, holds the horn in contact with the inner sides of the two parts 9 and 10 of said housing. A ring 14 of sheet metal having U-shaped cross section is located around the contacting edge portions of the two parts 9 and 10 and clamped thereagainst holding the said parts against separation. Ring 14 extends entirely around the housing except at the lower side thereof, being parted at this point and having its ends closely adjacent to each side of the neck 1 where it passes downwardly through an opening in the lower side of the housing.

The housing and horn, as thus assembled, are applied to a base which may be made of

wood or any other suitable material. The base includes an upper section 15 and lower section 16. The upper section 15 is suitably curved at its upper edge and grooved to receive the lower side of the housing. It also has a vertical opening 17 therethrough for the neck 1 and the sleeve 7 of the horn to pass through. The lower section 16 of the base has a large cylindrical recess 18 made therein upwardly from its lower side, the central vertical axis of which is substantially coincident with the axis of the opening 17.

When the horn and housing have been applied to the base the sleeve 7 extends below the lower end of the vertical opening 17 and is then provided with a nut 19 screwed on the exterior threads of the sleeve, which nut fits in a recess 20 of larger diameter than the opening 17 and at the lower end thereof. Accordingly, when the nut 19 has been applied and comes against the shoulder at the upper side of the recess 20 it draws the horn downwardly against the rod 12 and in this manner draws the housing at its lower side downwardly against the upper section 15 of the base thereby firmly securing all of the parts together.

In the recess 18 previously described the usual loud speaker unit 21 of any desired type is located the same being attached to the sleeve 7 by connecting an exteriorly threaded projecting sleeve 22 at its upper side with the interiorly threaded lower end of the sleeve 7 as shown in Fig. 3.

When the horn is thus placed within and assembled with the housing and the base, a very firm structure is produced and one incapable of excess vibration. The side 4 particularly of the horn makes firm contact with the side 9 of the housing and excess vibration which would produce blasting is eliminated, while the housing side 9 acts in a measure as a sounding board to amplify and modulate the sound emitted. This invention of an amplifier for loud speaking units has proved very practical and useful. Sound passing from the mouth of the horn is directed outward through the openings made in the front side 10 of the housing. As before stated the firm engagement of the horn with the sides 50 of the housing is a feature of the construction which is very desirable and necessary for the attaining of the best results, making a substantial sound board which absorbs excess vibrations, eliminates blasting and vibrates in synchronism with the sound waves to properly reproduce, modulate and amplify the same. The construction also adapts itself for an exceptionally practical assembly of the parts which go to make up the structure. The invention is defined in the appended claims and is to be considered comprehensive of all forms of structure coming within their scope.

I claim:

1. In an amplifying horn, a vertical neck, 60 a metal sleeve secured to said neck at its lower

end to which a loud speaker unit is adapted to be attached, said neck being extended to one side and upwardly and progressively enlarged for a distance and then curved in a reverse direction and formed into a bell with 70 front and rear sides having their lower edges lying in the same horizontal plane, said sides converging upwardly toward each other and also toward each other at their outer edges away from said enlarged portion of the neck 75 and integrally joined with each other.

2. In a construction of the class described, a housing comprising, two conical housing members having their base edges located against each other in a vertical plane, means 80 for securing said members together, the front member having openings therethrough, and an amplifying horn located in the housing, having a neck extending through the lower side of said housing and, within the housing 85 being turned laterally and upwardly and enlarged progressively away from said neck and terminating in a relatively large bell having an open lower side, the front and rear sides of the bell being shaped to lie against 90 the inner sides of said front and rear members of the housing at their upper portions.

3. A construction containing the elements in combination defined in claim 2, said rear side of the horn where it engages against the 95 rear side of the inner member of the housing being cemented thereto, substantially as described.

4. An amplifying construction comprising a hollow housing, a horn located within said 100 housing and having a neck extending through the lower side thereof, said horn being curved laterally and upwardly away from the upper end of the neck and enlarging progressively 105 away from said neck and being thence curved back over the neck and formed into a relatively large bell having an open end, the lower edges of the sides of said bell at said open end thereof lying in the same horizontal plane, the front side of said housing having 110 openings for the escape of sound, said front side being located substantially at right angles to the plane of the open end of said bell.

5. In a sound amplifier, a hollow housing 115 having an opening in its lower side, a base having a seat formed at its upper side against which the lower side of the housing bears, a horn located within the housing and having a depending neck extending through the opening in the lower side of the housing, said base having a vertical opening through which the neck also extends, means threaded on to the lower end of the neck and against the base for drawing the horn in a downward direction, and means extending through the housing under the upper portion of the horn whereby when said horn is drawn downwardly the housing is also drawn downwardly 125 against said seat on the base.

6. In a sound amplifier, a hollow housing having an opening in its lower side, a horn located within said housing having a neck extending through said opening in the housing, said horn being curved laterally and upwardly away from the upper end of the neck and enlarged progressively away therefrom and terminating in a bell filling the upper portion of the housing and having its lower edges located in a horizontal plane, a rod extending through and between the sides of the housing directly underneath the lower edges of the sides of said bell of the horn, a base formed at its upper side with a seat for the lower side of the housing and with a vertical opening therethrough through which the neck of the horn passes, and a nut threaded on to the lower end of the neck against the under side of the base to thereby draw the horn downwardly against said rod and,

through said rod, draw the housing into firm engagement with said seat on the base.

7. In a sound amplifier, a housing comprising, a conical back member, a conical front member located with its base edges 25 against the like edges of the back member, means for securing said housing members together at their edges, said front member having openings therethrough, and a horn having an enlarged bell with an open lower 30 side substantially filling the upper portion of the housing and with its front and rear sides bearing against the front and rear sides of the housing, said horn also having a neck portion extending downwardly and under 35 said bell and through the lower side of the housing.

In testimony whereof I affix my signature.

JACOB KERSTEN.
